UNITED STATES PATENT OFFICE.

WILLIAM J. VAN OSDEL, OF CHICAGO, ILLINOIS, ASSIGNOR OF ONE-HALF TO LOUIS SPERLING, OF CHICAGO, ILLINOIS.

HAIR-CUTTER.

1,321,496.

Specification of Letters Patent. Patented Nov. 11, 1919.

Application filed December 14, 1918. Serial No. 266,659.

To all whom it may concern:

Be it known that I, WILLIAM J. VAN OSDEL, a citizen of the United States, residing at Chicago, in the county of Cook and the State of Illinois, have invented certain new and useful Improvements in Hair-Cutters, of which the following is a specification.

This invention relates to improvements in hair cutters but more specifically to the power mechanism for actuating the same, and one of the objects of the invention is to provide an improved, simple, compact and convenient arrangement of the parts whereby the device may be easily manipulated by the barber, and which will at the same time be effective and efficient in operation.

A further object is to provide improved means whereby access may be readily had to the parts, and at the same time to provide a structure embodying a bearing having a rotatable shaft mounted therein and means whereby the bearing will be air cooled so as not to heat the hand of the operator.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which—

Figure 1 is a top plan view of an improved device of this character constructed in accordance with the principles of this invention.

Fig. 2 is a longitudinal sectional view as taken on line 2—2, Fig. 1.

Fig. 3 is a detail top plan view of the bearing member.

Fig. 4 is a horizontal sectional view of the bearing member and with other parts of the mechanism removed.

Fig. 5 is a detail sectional view on line 5—5, Fig. 1.

Fig. 6 is a detail sectional view taken on line 6—6, Fig. 1.

Fig. 7 is a side elevation of the operating lever for one of the cutters.

Fig. 8 is a top plan view of the parts shown in Fig. 7.

In the drawings the head of the clipper is of the ordinary and well known construction now in use comprising a knife 10 hav-

ing teeth 11 along one edge, and a co-operating knife 12 slidably mounted upon the knife 10 and having teeth 13 along one edge, co-operating with the teeth 11. Projecting upwardly from the cutter 10 is a stud 14 upon which is mounted an oscillating member 15 which is connected with the cutter 12 so as to impart thereto a motion relative to the cutter 10. Connected with this member 15 and forming a part thereof is a lever 16 one end of which is preferably bent at an angle thereto and the bent extremity is bifurcated as at 17 for a purpose to be set forth. This element 16 may be connected with the element 15 in any desired or suitable manner and as shown in Fig. 4, may comprise a pin or rivet 18 while the form as shown in Figs. 7 and 8 may comprise spaced depending ears 19 arranged at the forward end thereof and adapted to stand astride of the element 15. The stud 14 projects through the elements 15 and 16 and terminates in a threaded extremity to receive a thumb nut 20, which latter is adapted to hold a cap member 21 in position. This cap member is provided with an opening through which the stud 14 passes and the member extends over the cutter 12 and also the element 15, the element 16 passing between the cap 21 and the rear portion of the fixed cutter. The thumb nut 20 is provided for the purpose of holding the parts together and there is interposed between the thumb nut and the cap, a spring washer 22 so as to hold the parts under tension, and in order to limit the adjustment of the nut 20 in one direction and thereby control the tightening of the cap upon the cutter shaft so that it cannot be tightened to too great an extent, the cap is provided with a recessed portion surrounding the opening therethrough and the thumb nut is provided with a reduced extremity 24 adapted to enter the recess 23 and abut the shoulder formed thereby so that the nut can be secured upon the stud 14 only to a predetermined extent.

A handle 25 is connected with the cutter 10 and is of the ordinary and well known shape. A bearing member 26 is connected with the handle 25 in any desired or suitable manner such as by means of the fastening devices 27, and the bearing member is provided with a bearing 28 extending longitudinally therethrough. The inner end of the member 26 is provided with an enlarge-

ment 29 to form a shoulder 30. Rotatably mounted in the bearing is a shaft 31 having connected with one extremity thereof a worm 32 which is located within the enlargement 29 and which latter forms a chamber for the worm. The worm is connected with the shaft in any suitable manner and is of a diameter slightly larger than the diameter of the bearing 28 so as to 10 form a shoulder adapted to abut the shoulder 30. The end of the chamber 29 in alignment with the end of the shaft 31 is open and a bearing member 33 having a hardened bearing projection 34 is detachable secured in the end of the member 26 so that the end of the shaft 31 will rest against the projection 34 and this member 33 together with the shoulder 30 will hold the shaft 31 against an axial or longitudinal 15 shifting movement of the shaft within its bearing. The bearing member 33 may be held against accidental displacement in any suitable manner such as by means of a fastening device 35. The chamber 29 is provided with a laterally projecting portion 36 communicating therewith and this portion is provided with a stud or projection 37 connected to and extending from one of the walls of the chamber. Rotatably 20 mounted upon this stud 37 is a worm gear 38 which meshes with the worm 32 and the portion 36 of the chamber 29 is provided with an opening by means of which ready access may be had to the parts, and this opening is closed by a suitable closure 39 provided with an ear or extension 40 adapted to be seated in a recess 41 in the member 26, and is held in position by a suitable fastening device 42.

40 The wall of the portion 36 of the chamber 29 is provided with a slot 43 into which the bifurcated extremity of the lever 16 is adapted to project, and slidably mounted within the bifurcation 17 of the element 16 45 is a block 44 which is pivotally mounted upon a stud 45 projecting laterally and eccentrically from the worm gear 38.

Thus it will be seen that when the shaft 31 is rotated the worm gear connection will 50 oscillate the lever 16 and impart a sliding movement to the cutter 12 with relation to the cutter 11. The threads on the worm 32 are so arranged with respect to the worm gear 38 that during the operation of the 55 shaft, these threads will tend to hold the worm gear 38 against accidental displacement. By the provision of the chamber 29 with the enlargement 36, it will be manifest that this chamber will form a grease well 60 for maintaining the parts lubricated, the slot 43 being placed adjacent the top of the chamber will prevent the grease from flowing out of the slot. It will also be manifest that the removable element 33 permits 65 ready access to the end of the shaft.

The sliding block 44 reduces wear on the lever 16.

If desired a second handle member 46 may be provided and secured to the element 26 by suitable fastening devices 47. The exterior surface of the bearing member 26 is so shaped that it will be spaced from the handle members 25-46 and thereby form air circulation passages between the handles and the bearing member so that the bearing 75 member will be air cooled and obviates the necessity of the operator grasping the bearing member to hold the implement, and which would by means of the rotation of the shaft 31, cause the operator's hand to 80 become heated by the transmission of heat from the bearing member 26.

An oil hole 48 provided with a suitable closure may be provided in the bearing member for the shaft 31.

In order to operate the shaft, there is provided a flexible casing 49 having a reduced extremity 50 provided with a circumferential open groove 51. This reduced portion 50 is adapted to be inserted in the free extremity of the bearing member 26 and is held against displacement by means of a suitable fastening device such as a pin 52 passing through a suitable opening in the bearing member and which pin is held 95 in position by means of a spring 53 and a nut 54. A flexible driving shaft 55 is provided in the member 59 to project beyond the extremity of the reduced portion 50 and interlock with the end of 100 the shaft 31. With this improved construction it will be manifest that when the bearing member 26 is detached from the handle 25, the bearing block 44 and the bifurcation 17 of the lever 16 may be readily 105 separated without necessitating the dismantling or adjustment of any of the other parts of the mechanism, and by reversing the operation the bearing member may be again secured in position on the handle and 110 the operative connection between the parts reestablished.

What is claimed as new is:—

1. A motor driven hair clipper, embodying a handle, a cutter on one end of said handle, a reciprocating cutter co-operating with the cutter on said handle, an elongated bearing member extending longitudinally of and secured to but spaced from said handle, a gearing housing carried by the forward end of said bearing, gearing in said housing, an operable connection between said gearing and said reciprocating cutter, and a second handle extending longitudinally of the bearing member and secured to 120 but spaced from the bearing member and on the opposite side of the bearing member to that to which the first named handle is secured.

2. A motor driven hair clipper embody- 130

ing a handle; a cutter on the end of the handle, a reciprocating cutter coöperating with the cutter on said handle, an elongated bearing member extending longitudinally of and detachably secured to the handle, a 5 gearing housing carried by the forward end of the bearing and having an opening in the wall thereof, gearing in the housing, a separable and operative connection between said 10 gearing and said reciprocating cutter, the said connection embodying an arm extending into the gearing housing through the said opening, said arm having an elongated open ended slot, and a bearing slidable in the said slot and connected with one of the 15 gear elements whereby when said bearing member is detached from the said handle, the parts of the said operative connection between the gearing and cutter may be 20 freely separated while the other parts remain intact.

3. A motor driven hair clipper embodying a handle, a cutter on one end of the handle, a reciprocating cutter coöperating with the cutter on the handle, an elongated bearing member detachably secured to and extending lengthwise of the handle, a gearing housing carried by the forward end of the bearing member, a power shaft journaled in the bearing, one end of the shaft extending 25 into the said housing, an adjustable bearing connected with the first recited bearing in line with the said shaft and against which adjustable bearing the end of the shaft 30 abuts, a gear element within the housing and connected with the shaft, a second gear element within the housing and meshing with the first recited gear element, said housing having an opening in its wall, a 35 separable and operable connection between the second said gear element and the reciprocating cutter, the last recited connection embodying an arm extending into the housing through said opening and having 40 an elongated open ended slot, and a slidable 45 block operating in said slot and pivotally connected with the second recited gear element, whereby when the said bearing member is detached from the said handle, the 50 said block and arm may be freely separated

without dismantling any of the other parts of the device.

4. A motor driven hair clipper, embodying a handle, a cutter on one end of the handle, a reciprocating cutter coöperating with the cutter on the handle, a bearing member detachably secured to the said handle, gearing carried by a bearing member, and a freely separable and operable connection between the said gearing and the reciprocating cutter, the said connection embodying an arm having an open slot therein and a bearing connected with the gear element and freely movable in the slot, whereby when the said bearing member is detached from the said handle, the parts of the said operable connection may be freely separated without detaching or separating any of the other parts of the mechanism.

5. A motor driven hair clipper embodying a handle, a cutter on the end of the handle, a reciprocating cutter coöperating with the cutter on the handle, an elongated bearing member extending longitudinally of and detachably secured to the handle, a gearing 75 housing carried by the forward end of the bearing and having an opening in the wall thereof, gearing in the housing, a separable and operative connection between the said 80 gearing and the said reciprocating cutter. 70 the said connection embodying an arm extending into the gearing housing through said opening, said arm having an elongated open ended slot, a bearing slidable in the 85 said slot and connected with one of the gear elements whereby when said bearing member is detached from the said handle, the parts of the said operative connection between the gearing and cutter may be freely separated while the other parts remain intact, said gearing housing having an open 90 side to permit free access to the gearing and the bearing and slot connection therein, and a removable closure for the said open side 95 of the housing.

In testimony whereof I have signed my name to this specification on this 11th day of December, A. D. 1918.

WILLIAM J. VAN OSDEL.
